UNITED STATES PATENT OFFICE.

ERNEST RIEDEL AND JEROME FULHABER, OF PATERSON, NEW JERSEY.

HEATING APPARATUS.

SPECIFICATION forming part of Letters Patent No. 735,412, dated August 4, 1903.

Application filed March 24, 1903. Serial No. 149,355. (No model.)

To all whom it may concern:

Be it known that we, ERNEST RIEDEL and JEROME FULHABER, citizens of the United States, residing in Paterson, in the county of Passaic and State of New Jersey, have invented certain new and useful Improvements in Heating Apparatus; and we do hereby declare the following to be a full, clear, and exact description of the invention, such as will enable others skilled in the art to which it appertains to make and use the same, reference being had to the accompanying drawings, and to characters of reference marked thereon, which form a part of this specification.

Our invention relates to that class of heating apparatus in which a tubular system is employed for the circulation of hot water or steam; and it has for its principal object to provide a heating apparatus in which the desired conditions for giving off heat may be quickly reached and thereupon maintained with only the expenditure of the minimum amount of fuel.

The invention consists in an improved heating apparatus formed and arranged substantially as hereinafter described and finally embodied in the clauses of the claim.

The accompanying drawings fully illustrate our invention.

Figure 1 is a view in front elevation; Fig. 2, a vertical sectional view taken approximately just inside the adjacent side wall of the shell; Fig. 3, a horizontal sectional view on the line xx in Fig. 1, and Figs. 4 and 5 detail views.

Our apparatus is shown and will be herein described as comprising in a single organization two heat generating and dispensing units; but there is no reason why in so far as the spirit of the invention is concerned a single unit only may not be utilized.

The shell of the apparatus comprises a hollow base a , lined at the back and both sides and also divided substantially centrally by some refractory substance, such as fire-brick, as at b , a vertical drum c , resting on base a , and a cap d , surmounting the drum and having fitted to it the smoke-pipe e . At each side of the partition portion f of the fire-brick the base a is provided with a fuel-supply door g and an ash-pit door h .

i denote two series of parallel rows of vertical tubes. At their tops these rows of tubes

communicate with corresponding series of horizontal tube-heads j , each of which has a smaller tube k leading up to and communicating with a loop l , which extends partly into the shell of the apparatus and in turn communicates with the circulation-pipe m of the radiating system. The two outer rows of tubes i in each series are extended farther downwardly, as at n , than the others. The thus lengthened tubes in each series communicate at the bottom with a horizontal tube-head o of substantially U shape, (see Fig. 3,) while the intermediate or relatively shorter ones communicate with a series of parallel horizontal tube-heads p . A loop q , arranged at the back lower portion of the shell, communicates on the one hand with the circulation-pipe m , and by means of series of tubes r and tubes s with tube-heads o and p , respectively.

It will be observed that tube-heads p and o are arranged, respectively, above and below the fuel-supply door g . The space t between them constitutes the fire-pot and has for its bottom a grate composed of a horizontal series of tubes u , which communicate with the tube-head o at the front, and at the back extend through and have support in the back wall of the ash-pit, whereupon by means of tubes v they communicate with the loop q . Loop q has a water-supply pipe w and a drain-cock x attached to it.

y is a steam-gage which surmounts a pipe z , which at its upper end is connected to the exposed portion of loop l and at its lower end to the return portion of pipe m . With pipe z communicates a water-gage 1. In the exposed portion of loop l are arranged two cut-off valves 2, and in each leg of loop q is arranged another cut-off valve 3. By this means either of the units may be cut off from the circulation. In communication with loop l are also safety-valves 4. 5 is an automatic diaphragm damper - regulator connected by a chain 6 with the ash-pit doors h and having its pipe 8 communicating with the portion of loop l which is relatively between valves 2 and circulation-pipe m .

In order to clear the fire-pot of ashes, we provide a rake 9, consisting of a series of parallel fingers 10, arranged on parallel rods 11 and so disposed as to take up in between the grate-

bars, said rods having their ends extending into guideways 12, which are arranged against the sides of the ash-pit and extend substantially horizontal except near the back, 5 where they curve slightly downwardly, as at 13. 14 is a draw-bar which is pivoted on the front rod 11 and is guided in an opening 15 in the base *a* over the ash-pit door.

In the use of our apparatus the tubular 10 structure contained within the shell being filled to the proper height with water and the fire being started the heating of the water in said structure will induce circulation up through the loop *l* and around by way of pipe 15 *m* back to said structure through loop *q*. It will be understood that in referring to the circulation we have in mind either employing the apparatus as the generator of a hot-water or steam system. If it is desired to operate only 20 one unit, one valve 2 and the corresponding valve 3 are closed, the fire for said unit being of course extinguished. The circulation under these circumstances then continues with the other unit as the generating medium. The 25 regulator for the dampers and the water and steam-gages having each a connection with the system at points relatively to the generating units, which are beyond the valves 2 and 3, said regulator and the gages are operative 30 at all times, whether one or both of said units is working; and since each unit has a safety-valve attached immediately thereto—*i. e.*, between valves 2 and 3—there is no danger of accident. It will be understood that that ar- 35 rangedment of the tubes *i* and tube-heads *o* and *p*, whereby a sort of a basket of tubes forms the fire-pot, is a feature of great advantage, especially in so far as expediting the action is concerned.

40 The raking of the ashes out of the fire-pot is effected, as will be obvious, by simply moving the rake 9 back and forth by means of the draw-bar 14.

We prefer to construct the drum *c* of sheet

metal and to insulate the portion of the tubu- 45 lar structure of each unit of the generator, which said drum directly incloses by a surrounding envelop 16 of asbestos.

Having thus fully described our invention, what we claim as new, and desire to secure by 50 Letters Patent, is—

1. In a circulating heating system, the combination of a circulating-pipe, loops communicating each with one end of said pipe, a generator consisting of a plurality of units each 55 comprising a plurality of tubular structures communicating at their upper portion with one of said loops and at their lower portion with the other loop, and valves arranged in said loops between each unit and the adjacent end of the pipe, substantially as described.

2. In a generator for a circulating heating system, the combination of parallel rows of upright tubes, the outer rows being extended 65 downwardly farther than the intermediate rows, substantially horizontal tubing connecting up the tubes in each row at the top, substantially horizontal tubes connecting up the tubes in each of the intermediate rows at their 70 lower ends, a substantially U-shaped and horizontal tubular structure connecting up the lower ends of the outer rows of tubes, and substantially parallel tubes arranged within, and approximately in the plane of, said U- 75 shaped tubing and communicating therewith, said last-named tubes and the U-shaped tubing forming a grate, substantially as described.

In testimony that we claim the foregoing 80 we have hereunto set our hands this 21st day of March, 1903.

ERNEST RIEDEL.
JEROME FULHABER.
